UNITED STATES PATENT OFFICE.

SALMON THOMPSON, JR., OF CEDAR FALLS, IOWA.

BURNER.

1,149,870.

Specification of Letters Patent. Patented Aug. 10, 1915.

Application filed May 23, 1914. Serial No. 840,530.

To all whom it may concern:

Be it known that I, SALMON THOMPSON, Jr., a citizen of the United States of America, and a resident of Cedar Falls, Black-hawk county, Iowa, have invented certain new and useful Improvements in Burners, of which the following is a specification.

My invention relates to improvements in burners, and especially to processes whereby 10 water and kerosene or some like hydrocarbon may be mingled, a wick immersed therein, and the wick then ignited to induce simultaneous combustion of the oil and vaporization of the water, to thereby supply 15 a mingled volume of heated vapor and gases of combustion.

The above process, I have effected by the means which are hereinafter described and claimed, and as illustrated in the accompanying drawings, in which:

Figure 1 is a vertical section of a receptacle containing mingled oil and water with a wick immersed therein, before ignition, Fig. 2 is a vertical section of said receptacle 25 showing the said fluids commingled therein in a state of ebullition while the oil component is under combustion.

Similar numerals of reference denote corresponding parts throughout the several 30 views.

Referring first to Fig. 1, the numeral 1 denotes an open top receptacle containing both water and kerosene oil or other like hydrocarbon, in any relative proportion desired. The numeral 2 denotes a wick which may be a porous piece of dry wood or any other suitable material capable of becoming impregnated by the oil, and which may be 35 immersed in the mingled fluids.

Fig. 1 shows the condition of the mingled liquids before the ignition of the oil component, in which the lighter constituent floats upon the heavier.

Fig. 2 shows the apparatus after the ignition of the oil-soaked wick or block 2, and 45 in which the block and the surface of the oil is under combustion, creating sufficient heat to boil the water in said receptacle, thus placing the same in ebullition which permits the escape of steam, and thus intimately 50 commingles the oil and water in the receptacle, as shown at 5. In other words, the oil 3 and the water 4 form a heated emulsion 5, from which steam escapes simultaneously 55 with the production of the heated gases due to the combustion of the water gases and the oil, and furnishing a mingled volume of heated gases.

The wick or block 2 is but little, if any, consumed, since the oil and water become exhausted practically at the same time, leaving 60 the block but slightly charred.

A burner thus furnished may be used conveniently for any purpose for which heating 65 is required, and is very inexpensive.

Having described my invention, what I claim as new, and desire to secure by Letters Patent, is:

The process consisting of placing in an open receptacle a layer of water covered by 70 a layer of oil, then partially submerging in the oil a dry piece of wood or other porous substance, finally igniting the oil-impregnated wood and the surface of the oil in the receptacle and thereby heating and boiling 75 the water and oil, converting the water to steam, and separating the steam into its gaseous components, igniting and consuming the latter with the oil.

Signed at Waterloo, Iowa, this 7th day 80 of May, 1914.

SALMON THOMPSON, JR.
